CLAIM

The ornamental design for a lifting device, as shown.

DESCRIPTION

FIG. 1 shows a right-side rear perspective view of a first embodiment of the lifting device of our new design in a retracted configuration;

FIG. 2 shows a front elevation view of the first embodiment of the lifting device of our new design in a retracted configuration;

FIG. 3 shows a right-side elevation view of the first embodiment of the lifting device of our new design in a retracted configuration;

FIG. 4 shows a rear elevation view of the first embodiment of the lifting device of our new design opposite that of FIG. 2 in a retracted configuration;

FIG. 5 shows a left-side elevation view of the first embodiment of the lifting device of our new design opposite that of FIG. 3 in a retracted configuration;

FIG. 6 shows a top plan view of the first embodiment of the lifting device of our new design in a retracted configuration;

FIG. 7 shows a bottom plan view of the first embodiment of the lifting device of our new design opposite that of FIG. 6 in a retracted configuration;

FIG. 8 shows a left-side front perspective view of the first embodiment of the lifting device of our new design opposite that of FIG. 1 in a retracted configuration;

FIG. 9 shows a right-side rear bottom perspective view of the first embodiment of the lifting device of our new design in a retracted configuration;

FIG. 10 shows a left-side front top perspective view of the first embodiment of the lifting device of our new design opposite that of FIG. 9 in a retracted configuration;

FIG. 11 shows a right-side rear perspective view of the first embodiment of the lifting device of our new design in an extended configuration relative to the retracted configuration FIG. 1;

FIG. 12 shows a left-side front perspective view of the first embodiment of the lifting device of our new design opposite that of FIG. 11 in an extended configuration relative to the retracted configuration FIG. 8;

(Continued)

FIG. 13 shows a right-side rear bottom perspective view of the first embodiment of the lifting device of our new design in an extended configuration relative to the retracted configuration FIG. 9; and,

FIG. 14 shows a left-side front top perspective view of the first embodiment of the lifting device of our new design opposite that of FIG. 13 in an extended configuration relative to the retracted configuration FIG. 10.

The broken and/or evenly-spaced dashed lines are included to show environmental elements and/or supplemental structure(s) in the drawings that form no part of the claimed design.
